Filed Dec. 7, 1967, Ser. No. 9,689

Term of patent 14 years

(Cl. D61—1)

Fig. 1.

Fig. 2.

Fig. 3.

FIGURE 1 is a front, top, and side perspective of a motion picture camera, showing my new design with the lens cover open;

FIGURE 2 is a front, top, and opposite side perspective view with the lens cover closed; and

FIGURE 3 is a rear elevational view thereof.

Portions of the figures are diagonally lined to indicate transparency.

Portions of the figures are stippled to indicate contrast in appearance.

I claim:

The ornamental design for a motion picture camera, as shown and described.
